UNITED STATES PATENT OFFICE.

WILLIAM B. SMITH, OF BOISÉ, IDAHO, ASSIGNOR OF ONE-HALF TO WILLIAM A. KORTS, OF SAME PLACE.

DESIGN FOR A HOE.

SPECIFICATION forming part of Design No. 33,331, dated October 9, 1900.

Application filed August 28, 1900. Serial No. 28,359. Term of patent 14 years.

To all whom it may concern:

Be it known that I, WILLIAM B. SMITH, a citizen of the United States, residing at Boisé, in the county of Ada and State of Idaho, have 5 invented and produced a new and original Design for Hoes, of which the following is a specification.

My invention relates to a new and useful design for hoes, of which the following is a 10 specification, reference being had to the accompanying drawings, forming a part thereof.

Figure 1 is a perspective of my design. Fig. 2 is a plan view of the same.

The numeral 1 designates the blade of my 15 hoe, which is beveled at 2 to an edge. The handle 3 is set at an oblique angle to the direction of the blade 1, the arms 4 being of unequal length, and is inclined upward.

The essential feature of my design is the flat blade 1, with the handle 3 extending at 20 an oblique angle thereto and provided with unequal arms 4.

Having thus described my invention, what I claim as new, and wish to secure by Letters Patent, is—

The design for a hoe substantially as shown and described.

In testimony whereof I have hereunto set my hand in presence of two subscribing witnesses.

WILLIAM B. SMITH.
